(57) **CLAIM**

The ornamental design for an undergarment as shown and described.

DESCRIPTION

FIG. 1 is a front perspective view of the undergarment. The undergarment is symmetrical from left to right.

FIG. 2 is a rear perspective view of the undergarment. The undergarment is symmetrical from left to right; and,

FIG. 3 is a bottom plan view of the undergarment. The broken lines shown illustrating portions of the undergarment in the drawings represent portions of the article which form no part of the claimed design.

The broken lines illustrating a human figure represent environment of the claim and form no part of the claimed design.
